His Attorney.

UNITED STATES PATENT OFFICE.

FRANK F. BRADSHAW, OF YAZOO CITY, MISSISSIPPI.

APPARATUS FOR DELIVERING ARTICLES TO AIRCRAFT.

Application filed December 27, 1929. Serial No. 433,463.

To all whom it may concern:

Be it known that I, FRANK F. BRADSHAW, a citizen of the United States, residing at Yazoo City, in the county of Yazoo and State of Mississippi, have invented a certain new and useful Improvement in Apparatus for Delivering Articles to Aircraft, of which the following is a specification.

My invention relates to improvements in apparatus for delivering articles to aircrafts.

It is particularly adapted for delivering mail pouches to flying machines.

The object of my invention is to provide a novel apparatus of the kind described, which is cheap to construct, which is strong and durable and not liable to get out of order, which is efficient in operation, and which can be operated without danger to those on the aircraft or on the ground adjacent to the apparatus.

The novel features of my invention are hereinafter fully described and claimed.

In the accompanying drawings which illustrate the preferred embodiment of my invention,

Fig. 1 is a perspective view of my improved apparatus.

Fig. 2 is an enlarged top view of a portion of the apparatus.

Fig. 3 is a view partly in side elevation and partly in vertical section of what is shown in Fig. 2.

Fig. 4 is a top view of the article carrying device shown in solid lines in the open position and shown in dotted lines in the closed or gripping position.

Fig. 5 is a front elevation of the rope operated detent which holds the jaws of the gripping device in the open position.

Similar reference characters designate similar parts in the different views.

1 designates a mail bag adapted to rest upon a suitable support comprising, in the form shown, two horizontal parallel members 2, which are spaced apart and have diverging receiving ends between which is adapted to pass a trailing device, such as a rope or cable 3 which depends from an aircraft.

The members 2 are mounted near their middle portions upon two transverse hori-

zontal members 4 mounted adjacent their outer ends upon posts 5. The diverging ends of the members 2 are mounted upon two members 6 which are respectively mounted on the two outermost posts 5 and upon two posts 7 disposed at the rear of the posts 5.

The diverging portions of the members 2 serve to guide the rope or cable 3 between the members 2 and into operative relationship to an article carrying device comprising, preferably the following described parts.

Two jaws 8 are disposed one above the other and are provided at their rear ends and inner edges with projections 9. Mounted between the jaws 8 is a jaw 10 having at its rear end and inner edge a projection 11. The jaws 8 and 10 are pivoted on a vertical pin 12. For normally forcing the jaws 8 and 10 to the closed gripping position, I provide a coil spring 13 the ends of which are respectively secured to the forward ends of the jaws 8 and 10, the tension of the spring 13 being such as will tend to close the rear ends of the jaws. Connected at its ends to the forward portions of the jaws 8 and the jaw 10 is a flexible member 13' which may be elastic, if desired to reduce shock, and to which the mail pouch 1 is adapted to be attached by a strap 14.

For releasably holding the jaws open, as shown in Fig. 2 and in solid lines in Fig. 4, I provide a detent member 15, which may be cylindrical and which has on its under side a projection 16 adapted to be fitted in two notches 16' provided respectively in the inner edges of the members 8 and 10. Teeth 17 may be provided on the upper side of the member 15, so that the latter may be readily engaged with the cable or rope 3, so that the detent will be tipped by the rope out of locking engagement with the jaws 8 and 10. When this occurs, the spring 13 will close the jaws 8 and 10 upon the rope 3 so that the latter is firmly gripped by the jaws. The aircraft in passing forwardly, that is to the left, as viewed in Figs. 1, 2 and 3, will, through the intermediacy of the cable 3, carry the article carrying device off from its support, and with it the mail bag or pouch 1, the weight of the latter tending to make the jaws 8 and 10 tightly grip the rope.

or cable 3. The projections 9 and 11 prevent the rope or cable being pulled from between the jaws 8 and 10 at the rear ends thereof.

For guiding the rope or cable 3 to and between the diverging ends of the members 2, I provide two forwardly and, preferably, downwardly inclined converging guiding members 18, the forward or lower ends of which are respectively attached to the rear ends and inner edges of the diverging portions of the members 2. The rear or upper ends of the guiding members 18 are respectively attached to the upper inner ends of the members 19, the latter being spaced widely apart and inclining upwardly and inwardly. Each member 19 is mounted adjacent to its outer end upon two vertical posts 20, the inner one of which is the higher.

20 To prevent liability of the rope being fouled by the supporting posts, the members 19, 4 and 6 overhang at their inner ends.

In operating the invention, the air craft takes a line of travel to the left, as viewed in Fig. 1, such that the rope 3 will be trailed between the inner ends of the members 19 and between the members 18. The latter will guide the rope or cable between the diverging ends of the members 2 and into contact with the upwardly extending teeth 17 of the detent 15. The latter will be tilted by the rope or cable to a position in which the projections 16 will be withdrawn from the notches 16', thus permitting the spring 13 to close the jaws 8 and 10. The said jaws will grip the rope or cable 3. The forward movement of the aircraft will cause the rope or cable to lift the article carrying device and with it the mail bag 1, the detent 15 being dropped for use in connection with another article carrying device.

Either the flexible member 13' or the strap 14 may, if desired, be resilient so as to reduce the shock occasioned by the lifting of the mail pouch.

After the rope has operatively engaged the article carrying device, the rope may be drawn upwardly, so that the mail pouch and article carrying device can be taken on board the aircraft.

By having the inclined members 19 spaced widely apart and their inner ends at a relatively high elevation, the operator of the aircraft will experience no difficulty in manipulating the aircraft so that the rope or cable 3 will be reliably guided into operative relationship with the detent 15. It will be noted that the jaw 10 is mounted between the ends of the jaws 8, and that the projection 11 will enter between the two projections 9 of the jaws 8. By means of this construction, the gripping device comprising the jaws 8 and 10 will grip and securely hold a trailing device, such as a rope or cable, which is of uniform diameter

throughout, and which has no knots or protuberances, so that the trailing device need have no hook nor enlarged portion which might become fouled with anything on the ground. Liability of accident or injury or damage to the aircraft, due to such fouling of the trailing rope or cable, is avoided.

I do not limit my invention to the structure shown and described, as many modifications, within the scope of the appended claims, may be made without departing from the spirit of my invention.

What I claim is:

1. In an apparatus of the kind described, an article carrying device having means for gripping a flexible trailing device or cable, and movable from an open position to a closed gripping position and having means by which the weight of the article carried tends to force the gripping means to the closed position, and means releasable by said trailing device for holding the gripping means in the open position, substantially as set forth.

2. In an apparatus of the kind described, an article carrying device having two gripping jaws adapted to grip a flexible trailing device or cable, means by which the weight of the article carried tends to close the jaws, and means releasable by the trailing device for holding the jaws open, substantially as set forth.

3. In an apparatus of the kind described, an article carrying device having two gripping jaws adapted to grip a flexible trailing device or cable, means by which the weight of the article carried tends to close the jaws, means for normally forcing the jaws to the closed position, and means releasable by said trailing device for holding the jaws open, substantially as set forth.

4. In an apparatus of the kind described, an article carrying device having two gripping jaws adapted to grip a flexible trailing device or cable, means by which the weight of the article carried tends to close the jaws, means releasable by the trailing device for holding the jaws open, and means for guiding the trailing device into operative relationship with said jaws, substantially as set forth.

5. In an apparatus of the kind described, an article carrying device having two gripping jaws adapted to grip a flexible trailing device or cable, means by which the weight of the article carried tends to close the jaws, means for normally forcing the jaws to the closed position, means releasable by the trailing device for holding the jaws open, and means for guiding the trailing device into operative relationship with said jaws, substantially as set forth.

6. In an apparatus of the kind described, an article carrying device having two gripping jaws, a third jaw pivoted to said two

jaws and in the closed position being adapted to enter between the said two jaws, the outer ends of the jaws being provided respectively with inwardly extending projections which are adapted to overlap each other in the closed position, means for normally forcing the jaws to the closed gripping position,

and means adapted to be released by being struck by a flexible trailing device or cable, for holding the jaws in the open position, substantially as set forth.

In testimony whereof I have signed my name to this specification.

FRANK F. BRADSHAW.
